ORRIN B. ZOLINE, OF NEW YORK, N. Y., ASSIGNOR TO BRAND & OPPENHEIMER, INCORPORATED, OF NEW YORK, N. Y., A CORPORATION OF NEW YORK.

SLITTING MACHINE.

Application filed July 10, 1925. Serial No. 42,673.

My invention relates to slitting machines and has for its object to provide a machine of novel construction for slitting tubular material lengthwise in an efficient and continuous manner. My invention contemplates particularly the provision of a machine for rapidly slitting tubular fabric as it comes from a sewing machine, into flat biased sheets. Other objects of the invention will appear from the description hereinafter and the features of novelty will be pointed out in the claims.

In the accompanying drawings, which illustrate an example of the invention without defining its limits, Fig. 1 is a plan view of the machine; Fig. 2 is an end elevation partly in section, looking in the direction of the arrow in Fig. 1; Fig. 2 is a side elevation and Fig. 4 is a detail view showing the cutting mechanism.

As shown in the drawings the machine comprises a frame 10 of suitable form and dimensions and including a horizontal bed-plate 11 which in the illustrated example is continued at one end beyond the frame 10 in the form of a shelf 12 and bearing brackets 13. In its illustrated form, the machine includes a shaft 14 journalled in the latter and carrying a roller 15, the surface of which is preferably roughened for instance by being covered with sand-paper or emery cloth to provide a good gripping surface for the purpose to be more fully set forth hereinafter. A pulley 16 is fixed upon the shaft 14 which projects beyond the one bearing-bracket 13 for accommodating the same, said pulley being connected by means of a belt 17 with a pulley 18 which is mounted upon a drive shaft 19 as shown in Figs. 1 and 2. By a suitable arrangement of pulleys or their equivalent, the roller 15 may be driven at a higher surface speed than the feed rollers 33 and 33^a so that the material, after having been slit, is efficiently withdrawn from the machine as will appear more fully hereinafter. The shaft 19 further carries a second pulley 20 which in turn is connected, by means of a belt 21, with another pulley 22 carried by a stud-shaft 23 journalled in a bearing 24; the latter is secured upon a bracket 25 projecting from the frame 10 as illustrated in Figs. 1 and 3. The shaft 19 is rotatably mounted in bearings 26 and 26^a, comprising parts of stationary brackets 27 and 27^a fastened upon and projecting up-

wardly from the bed-plate 11, suitable provision being made to prevent lengthwise movement of said shaft in said bearings without interfering with its rotation therein. The stationary bracket 27 is continued in the form of a horizontal arm 28 provided at its free end with a vertical bearing 29 in which an upright shaft 30 is journalled; the latter in addition is rotatably mounted in a second vertical bearing 29^a located in spaced axial registry with the bearing 29 and forming part of a horizontal arm 31 as shown in Fig. 2. The arm 31 in turn comprises part of an auxiliary bracket 32 which, in the illustrated example, is an independent element fixed upon the bracket 27 although it will be obvious that the brackets 27 and 32 may be cast or otherwise constructed as an integral unit; in any case, said brackets 27 and 32 comprise an auxiliary supporting means located upon the bed-plate 11. A roller 33 preferably having a concave surface is fixed upon the shaft 30 between the bearings 29 and 29^a, the arrangement being such that said shaft 30 is fixed against vertical movement in said bearings but is free to rotate therein. The upright shaft 30 is actuated by means of a bevel-pinion 34 which meshes with a similar bevel-pinion 35 fixed upon the driving shaft 19 as shown in Fig. 2. A companion roller 33^a of corresponding concave form is carried by a second upright shaft 30^a in transverse registry with the roller 33 as shown in Figs. 1 and 2, said shaft 30^a being journalled in vertical bearings 29^b and 29^c located in spaced axial registry with each other; in the illustrated example, the bearings 29^b and 29^c are carried by upright brackets 34 and 35, the latter being fastened upon and supported by the former, although it will be obvious that said brackets 34 and 35 also may be cast or otherwise constructed in the form of an integral unit. The roller 33^a is located between the aforesaid bearings 29^b and 29^c and is fastened to the shaft 30^a in a manner to prevent lengthwise movement thereof in said bearings without interfering with the rotation of said shaft therein. In any case, the bracket 34 projects upwardly from a carrier 36 which is slidably mounted upon a horizontal guide 37 forming part of or secured upon the bed plate 11 as shown in Fig. 2, suitable devices such as set screws 38 being provided for fixing the carrier 36

in an adjusted position on said guide 37. The carrier 36 is further provided with a bearing 39 located on the bracket 34 and with an additional bearing 39^a through both of which the shaft 19 passes loosely so that said bearings 39 and 39^a are capable of lengthwise movement thereof as the carrier is adjusted on the guide 37. A bevel pinion 35^a is slidably mounted on the shaft 19 adjacent to the bearing 39^a and is keyed to said shaft to rotate therewith by means of a set screw 40 which projects into a key-way 41 extending lengthwise of the shaft 19 as illustrated in Fig. 2; the bevel pinion 35^a meshes with a bevel pinion 34^a fixed upon the shaft 30^a.

The rollers 33 and 33^a are arranged adjacent to rollers 42 and 42^a respectively, the latter having convex surfaces which fit the concave surfaces of the rollers 33 and 33^a as shown in Fig. 2. The rollers 42 and 42^a are rotatably mounted upon upright studs 43, the heads of which are countersunk in members 44, and the free ends of which are screwthreaded into companion members 44^a as shown in Fig. 2; the members 44 and 44^a of each pair are carried by bolts 45 which are slidably mounted in spreaders 46 and 46^a respectively. As shown in Fig. 2, springs 47 surround the bolts 45 in recesses 48 of the spreaders 46 and 46^a and bear with one end against the members 44 and 44^a and with the other ends against the inner end walls of said recesses 48 so that the rollers 42 and 42^a are normally forced toward the rollers 33 and 33^a and are capable of yielding against the tension of said springs; the heads 49 of the bolts 45 are countersunk in the spreaders 46 and 46^a and serve to arrest the outward movements of the rollers 42 and 42^a relatively to said spreaders 46 and 46^a. The latter extend lengthwise of the machine as shown in Figs. 1 and 3 and are mounted upon a cross-bar 50 extending transversely across the machine and supported upon brackets 51 at a distance above the bed-plate 11; in the preferred arrangement the spreaders 46 and 46^a are adjustable toward and away from each other and are fixed in adjusted positions in any convenient manner as by means of clamping plates 52 and clamping bolts 53 as shown in Fig. 3. The free ends of the spreaders 46 and 46^a are preferably curved as indicated at *a* and the outer surfaces thereof, at least for a part of the length of each spreader, are curved as indicated at *b* in arcs corresponding to the curvature of the convex rollers 42 and 42^a as illustrated in Fig. 2; it will, of course, be understood that the spreaders 46 and 46^a are suitably recessed for the proper accommodation of the rollers 42 and 42^a and their associated elements as shown in Fig. 3.

The cutting mechanism whereby the tubular material is progressively slit in the direction of its length, comprises a rotatable cut-

ter 54 carried by a shaft 55 journaled in bearings 56; the latter, as shown in Fig. 2, comprise parts of the horizontal member 31 constituting a part of the auxiliary bracket 32. In the preferred arrangement, a suitable guard 57 is provided for the cutter 54 to prevent unintentional contact therewith by an attendant; the cutter is actuated by means of a pulley 58 secured upon the shaft 55 and connected by means of a belt 59 with a pulley 60 carried by the stud-shaft 23. A horizontal guide member 61 is fastened at one end upon the cross-bar 50 and projects therefrom toward the cutter 54; the free end of said member 61 is preferably forked at 62 to straddle the cutter 54 as shown in Figs. 2 and 4.

The machine may be driven from any suitable source of power, the driving means in the illustrated example comprising a pulley 63 carried by the stud-shaft 23 and connected by means of a belt 64 with a source of power.

When used for slitting tubular fabric, for which purpose the machine is particularly adapted, it may include a turn-table 65 rotatably mounted upon a suitable support 66 and rotated, in a predetermined manner, for instance by means of a pulley 67 and a belt 68; the turn-table 65 constitutes a support for a receptacle 69 in which tubular fabric 70 in the twisted condition in which it issues from the sewing machine is contained. It will be understood that the tubular fabric is produced in any conventional manner.

In describing the operation of the machine it will be assumed that it is being used for slitting tubular fabric for which it is particularly adapted.

Under such conditions, a receptacle 69 containing a supply of the fabric 70 in twisted form as it comes from the sewing machine is placed upon the turn-table 65 and the end of said fabric is pulled over the spreaders 46 and 46^a and between the feed rollers 33 and 42 and 33^a and 42^a respectively. Either at this stage or previously thereto, the carrier 36 has been shifted on the guide 37 to the right in Fig. 2 in order to permit an adjustment of the spreader 46^a to a point at which the distance between the surfaces *b* of the two spreaders will correspond to the dimensions of the tubular fabric 70 which is to be slit. This adjustment of the spreader 46^a is accomplished by releasing the clamping plate 52 and bolt 53 to permit said spreader to be shifted lengthwise of the cross-bar 50 after which said plate and bolt are tightened up to fix said spreader in its adjusted position. The carrier 36 is then shifted back toward the left in Fig. 2 to bring the roller 33^a into proper engagement with the fabric 70 on the spreader 46^a; if any adjustment between the rollers 33 and 42 is required to bring the same into gripping

engagement with the fabric 70, this may be effected by adjusting the spreader 46 on the cross-bar 50 in the manner previously described with respect to the spreader 46^a. The machine is then set in motion by means of the pulley 63 and belt 64, whereby motion is imparted to the shaft 19 and the rollers 33 and 33^a; at the same time, the cutter 54 is actuated through the medium of the belt 59 and pulleys 58 and 60. The material 70 is then fed in the direction of its length by the action of the rollers 33 and 33^a in cooperation with the rollers 42 and 42^a, the latter serving to yieldingly press the material against the rollers 33 and 33^a respectively and being themselves operated by frictional engagement therewith. As the material is thus fed along, the cutter 54 will slit the same until finally the material is passed over and in surface engagement with the roller 15 which is driven by means of the belt 17 and pulleys 16 and 18. The outer surface of said roller 15 being roughened by being covered with sand paper or the like, it will grip the material and exert a pull thereon; because of the fact that the roller 15 is driven at a higher surface speed than that of the rollers 33 and 33^a, the speed at which the material is fed by said rollers will be slightly less than the speed at which the roller 15 tends to advance said material. As a result of this, the material 70 is held under a tension or in other words is maintained in a taut condition between the rollers 33 and 33^a and the roller 15 whereby the slitting action of the cutter 54 is materially facilitated. At the same time, the material after having been slit is efficiently removed from the machine. It will be noted that at the slitting point, the material 70 passes over the forked end 62 of the guide member 61 and that after it is slit, said material travels beneath the cross-bar 50 and gradually opens up into the flat sheet-like form in which it passes over the roller 15. In this way, the material is continuously fed along at the slitting point and is progressively slit in the direction of its length and as this slitting occurs, the material opens up flat under the cross-bar 50 as indicated in Figs. 1 and 3. The fabric or material 70 is produced in its tubular form in such a manner that when slit, the resulting flat sheets are cut on the bias. As the travel of the material into the machine progresses, the turn-table 65 is rotated in a manner and at a speed to progressively untwist the fabric or material as it passes from the receptacle 69 so that the tubular material passes in a smooth condition over the spreaders 46 and 46^a in a uniform manner and without interruption as long as the machine is in operation. The shelf 12 prevents sagging of the material into the mechanism on the machine side of the roller 15 if anything occurs to interrupt the action of the latter. If desired, the shelf 12 may be positioned in the machine in a manner to guide the slitted material out of the machine by gravity in which case the roller 15 and its associated parts may be omitted.

The adjustment of the spreaders permits the machine to accommodate tubular material of various sizes and at the same time makes it possible to effect a most efficient cooperation between the rollers 33, 33^a and 42, 42^a respectively. The latter being resiliently mounted not only exert a most efficient gripping action in the material to facilitate the feeding action of the rollers 33 and 33^a but are capable of yielding relatively to the last named rollers if, in the operation of the machine, this becomes necessary.

The machine is simple in construction and efficient in operation and requires no skilled attention in the performance of its functions.

Various changes in the specific form shown and described may be made within the scope of the claims without departing from the spirit of my invention.

I claim:

1. In a machine for slitting tubular material, the combination of slitting mechanism, spreaders adjustable in directions toward and away from each other over which the tubular material passes to said slitting mechanism, and feeding devices located partly within said spreaders and partly exteriorly thereof for feeding said tubular material lengthwise of said spreaders.
2. In a machine for slitting tubular material, the combination of a rotatable slitting knife, a pair of cooperating spreaders adjustable toward and away from each other over which the tubular material passes to the rotatable slitting knife, feed rollers resiliently mounted in said spreaders and effective upon the inner surface of said tubular material, cooperating feed rollers arranged to clamp the fabric against said first named feed rollers, and means for actuating said last named feed rollers to feed the tubular material lengthwise of said spreaders.
3. In a machine for slitting tubular material, the combination of a rotatable slitting knife, a pair of cooperating spreaders adjustable toward and away from each other over which the tubular material passes to the rotatable slitting knife, feed rollers resiliently mounted in said spreaders and having convex surfaces effective upon the inner surface of the tubular material, cooperating concave feed rollers for clamping the material against the convex feed rollers, at least one of said concave feed rollers being adjustable toward and away from the cooperating convex feed roller, and mechanism for operating said concave feed roller to feed the material lengthwise of said spreaders.

4. In a machine for slitting tubular material lengthwise, the combination of a supporting frame, a cross bar mounted thereon, a pair of spreaders adjustably mounted upon said cross bar, a rotatable slitting knife mounted upon said supporting frame between said spreaders and at an intermediate point thereof, convex feed rollers resiliently mounted on said spreaders, concave feed rollers cooperating with said convex feed rollers, a carrier for one of said concave feed rollers adjustably mounted upon said supporting frame for adjusting said concave feed roller toward and away from the cooperating convex feed roller, and mechanism for actuating said concave feed rollers.
5. In a machine for slitting tubular material, the combination of a bed-plate, auxiliary supporting means located thereon, a rotatable slitting knife mounted on said auxiliary supporting means, a driven feed roller carried by said auxiliary supporting means, a carrier adjustably mounted on said bed-plate, a driven feed roller supported upon said carrier and adjustable thereby toward and away from the companion feed roller, a pair of cooperating spreaders over which the tubular material passes to the slitting knife and feed rollers mounted upon said spreaders and cooperating with said driven feed rollers to feed the tubular fabric lengthwise of said spreaders.
6. In a machine for slitting tubular ma-
- terial, the combination of slitting mechanism, spreaders adjustable in directions toward and away from each other over which the tubular material passes to said slitting mechanism, feeding devices located partly within said spreaders and partly exteriorly thereof for feeding said tubular material lengthwise of said spreaders and mechanism coacting with the slit material for maintaining said material under a tension at the slitting point.
7. In a machine for slitting tubular material lengthwise, the combination of a supporting frame, a cross bar mounted thereon, a pair of spreaders adjustably mounted upon said cross bar, a rotatable slitting knife mounted upon said supporting frame between said spreaders and at an intermediate point thereof, convex feed rollers resiliently mounted on said spreaders, concave feed rollers cooperating with said convex feed rollers, a carrier for one of said concave feed rollers adjustably mounted upon said supporting frame for adjusting said convex feed roller toward and away from the cooperating concave feed roller, mechanism for actuating said concave feed rollers, and a friction roller effective upon the slit material for placing said material under tension at the slitting point.

In testimony whereof I have hereunto set my hand.

ORRIN B. ZOLINE.
